DIAL FACE FOR A SCALE

Alfred G. Stanton, Nyack, N.Y., assignor to Alfred Suter Co., Inc., New York, N.Y.

Filed Nov. 26, 1971, Ser. No. 202,711

Term of patent 14 years

Int. Cl. D10—04

U.S. Cl. D52—10 A

FIG. 1.

FIG. 2.

FIG. 3.

FIG. 1 is a top plan view of a dial face for a scale showing my new design;

FIG. 2 is a bottom end view thereof;

FIG. 3 is a sectional view taken along line 3—3 of FIG. 1.

I claim:

The ornamental design for a dial face for a scale, substantially as shown.
